UNITED STATES PATENT OFFICE

ROBERT S. BLAIR, OF STAMFORD, CONNECTICUT

MUFFLER CONSTRUCTION

Application filed May 29, 1924. Serial No. 716,615.

This invention relates to construction for mufflers for internal combustion engines.

One of the objects of the invention is to provide a construction of the above nature, practical and efficient and capable of meeting the requirements of use in a highly satisfactory manner. Another object is to provide a construction of the above nature adapted to operate dependably at all times to muffle the sound of the exhaust explosions from the engine. Another object is to provide such a muffler compact and simple in construction and inexpensive. Other objects will be in part obvious or in part pointed out herein-after.

The invention accordingly consists in the features of construction, combinations of elements, and arrangements of parts as will be exemplified in the structure to be hereinafter described and the scope of the application of which will be indicated in the following claims.

In the accompanying drawing in which are shown one or more various possible embodiments of the several features of this invention,

Figure 1 is a sectional view of a muffler.

Figure 2 is a sectional view of a modified form.

Figure 3 is an upward plan view of another modification.

Figure 4 is a front elevation of the modification shown in Fig. 2.

Similar reference characters refer to similar parts in the several views of the drawing.

Referring now to the drawing in detail, and first to Figure 1, there is shown the rear end portion of an exhaust pipe 10 of an internal combustion engine, for example, the engine of an automobile. The end of this exhaust pipe 10 opens into a chamber 11 formed by a casing 12. The exhaust pipe 10 extends into this chamber 11 to a substantial distance and the chamber, as will be seen, comprises a passage 45 which leads from the end of the exhaust pipe 10 preferably in substantially a circular path back about the end portion of the pipe. In front of the end 10^a of the pipe and also at the rear thereof, the chamber is enlarged as 50 indicated at 11^a and 11^b respectively. The

exhaust gases therefore being expelled rapidly from the end of the exhaust pipe creates an ejector action which tends to reduce the pressure in the portion 11^c of the passage. The passage or chamber 11 is provided with 55 a discharge opening 13 through the casing 12, this discharge opening being preferably at substantially the same distance in either direction from the end 10^a of the exhaust pipe.

The exhaust gases discharged from the end of the pipe 10 are projected through the portion 11^d of the chamber and upon reaching the discharge opening 13, tend to pass outwardly therethrough to the atmosphere. As 65 has been described, the ejector action reduces the pressure in the portion 11^c of the chamber, preferably so that the pressure at this portion is substantially below atmosphere. There is thus a tendency to divert a portion 70 of the gases tending to discharge through the exit opening 13 and to draw these gases through the portion 11^c back about the end of the exhaust pipe 10.

The explosions of the engine discharge 75 through the exhaust pipe 10 a rapid succession of discharges or puffs of exhaust gases. At each explosion of a cylinder of the engine, a large volume of gas is rapidly forced through the exhaust pipe. Between 80 the successive explosions, there is an interval when the volume of gas discharging from the pipe 10 is far less than the volume discharged at the instant of each explosion. Considering now one of these puffs of a 85 large volume of gas, this gas passes rapidly through the portion 11^d of the chamber and tends to pass out at the discharge opening 13. The ejector action, above described, 90 tends to prevent such exit, drawing a portion of the puff through the portion 11^c of the chamber. The extent of the ejector action and the size of the discharge opening 13 may be so proportioned that this diverted 95 portion of the puff of gas, after traversing the portion 11^c of the chamber, follows the main body of the puff through the portion 11^d and out through the exit 13 in the interval between this puff and the next succeeding puff. The action just described 100

tends, in effect, to create a balance of pressure between the inside of the casing and the outer air. With the parts properly constructed and proportioned, there may thus be had a substantially constant flow of exhaust gases through the discharge opening 13 and the noise of the exhaust is thereby effectually muffled.

Referring now to Figure 2, there is shown a modified form of this muffler. The exhaust pipe 10 from the engine cylinders projects into an enlarged opening 15 in a casing 16 which comprises a chamber 17 closed except for the opening 15 about the exhaust pipe 10. The walls of the chamber 17 are preferably curved substantially as shown and the gases discharged thereinto from the pipe 10 tend to swirl around therein, as indicated by the arrows. The rapid discharge of gases from the end 10^a of the exhaust pipe creates an ejector action which tends to draw air into the chamber 17 through the passage 15. At each explosion of the engine a puff comprising a large volume of gases is discharged into the chamber 17. The ejector action tends to prevent the immediate exit of a portion of this gas through the discharge passage 15. During the interval, however, between this puff and the next succeeding puff, the ejector action is substantially ineffective and the gases are permitted substantially free exit through the passage 15. The degree of ejector action accomplished, and the size of the discharge passage 15, may be so proportioned that the proper portion of each puff of gases may be prevented exit at the instant of the puff and permitted exit between puffs to obtain a substantially constant flow of gases outwardly through the passage 15.

Referring now to Figures 3 and 4, there is shown a casing 18, the inner walls of which are preferably substantially circular, and into which the gases from the exhaust pipe 10 are projected preferably substantially tangentially. The walls of the casing therefore cause the gases projected thereinto to swirl around as indicated by the arrows, the gases tending in their movement to fly outwardly in a radial direction due to centrifugal force. This movement of the gases tends to produce a reduction of pressure within the casing substantially at the center of curvature of the walls thereof. At the center the casing is provided with a discharge opening 19. At each puff of the exhaust, the swirling gases thereof cause a reduction of pressure in the vicinity of the opening 19, tending to prevent exit of a portion of the gases through the opening. Between puffs or explosions the reduction of pressure is not as great, and the opposition to the exit of the gases through the discharge opening 19 is therefore reduced. The parts may be so proportioned that a portion of each

puff discharges through the opening 19 at the instant of the puff and the remaining portion thereof discharges between this puff and the next succeeding puff. In this manner a substantially constant flow of the discharged gases may be had through the discharge passage 19.

It may be here noted that the muffler casings above described, and shown in Figures 1, 2 and 3, are in operation preferably positioned flat-wise or horizontal, that is so that the paths of the gases therethrough are substantially horizontal. In this manner the discharge openings 13, 15 and 19 open from the bottoms of the casings. This positioning provides for the convenient passing out through the discharge passages of unburned gases which find their way into the muffler casings, for example, when the engine is turned over without ignition.

From the above, it will be seen that there is herein provided apparatus which embodies the features of this invention and attains the objects thereof and that the same is adapted to meet the requirements of practical use in a highly satisfactory manner.

As many possible embodiments may be made of the above invention and as many changes might be made in the embodiment above set forth, it is to be understood that all matter hereinbefore set forth is to be interpreted as illustrative and not in a limiting sense.

I claim as my invention:

1. In muffler construction, in combination, a casing of rounded form, an exhaust conduit leading from an internal combustion engine and directed tangentially into said casing whereby gases therein will be whirled by the discharge from said conduit, said casing having a discharge port in injector relation to the entering gases, the total cross-section of the discharge port from the casing and its relation to the entering gases being such that the tendency to increased discharge due to increased pressure in the casing is substantially balanced by injector action whereby the discharge is constant and substantially uniform.

2. In muffler construction, in combination, a substantially circular casing, an exhaust conduit directed tangentially into said casing whereby gases therein will be whirled, said casing being formed to provide a single discharge port adjacent said conduit and so positioned that incoming gases will retard the discharge.

3. In muffler construction, in combination, a substantially circular casing, an exhaust conduit directed tangentially into said casing whereby gases therein will be whirled, said casing being formed to provide a single discharge port adjacent said conduit and so positioned that incoming gases will retard the discharge, and said casing being shaped and

mounted to permit unburned gas therein freely to flow out.

4. In muffler construction, in combination, a casing, an exhaust conduit directed into said casing in a tangential direction whereby gases therein will be whirled, and means forming a discharge port about the end of said conduit and so shaped and so related thereto that injector action of the incoming gases will retard the discharge of gases.

5. In muffler construction, in combination, a casing, an exhaust conduit directed into said casing in a tangential direction whereby gases therein will be whirled, and means forming a discharge port about the end of said conduit and so shaped and so related thereto that injector action of the incoming gases will retard the discharge of gases, the cross-section of said discharge opening being proportioned to permit the discharge to be continued while the exhaust is entering the casing.

6. In muffler construction, in combination, a casing, an exhaust conduit positioned to discharge directly into said casing, said casing being shaped to form a curved wall against which the entering gas is directed and a discharge port about the end of said conduit and independent of the path of the entering gas of substantially less diameter than that of the casing and so related thereto and of such cross-section that injector action of incoming gases will tend to retard the discharge to such extent as will compensate and substantially balance the tendency to increased discharge due to access of pressure from the incoming gases.

7. In muffler construction, in combination, a casing of rounded form, and an exhaust conduit directed into said casing in a tangential direction, said casing being formed to provide a discharge opening about the end of said conduit and in injector relation thereto and out of the path of travel of the incoming gases, whereby the discharge of gases may be continuous and substantially uniform.

8. In muffler construction, in combination, a casing of rounded form, an exhaust conduit directed tangentially into said casing, and means forming an outlet port about the end of said exhaust conduit in position to permit outgoing gases to be discharged independently of the path of travel of incoming gases and to be retarded by injector action of the latter, said casing being shaped and mounted to permit unburned gas therein freely to flow out.

In testimony whereof, I have signed my name to this specification this 27th day of May, 1924.

ROBERT S. BLAIR.
